UNITED STATES PATENT OFFICE.

GUSTAVE MARTIN FAUSER, OF NEW YORK, N. Y., ASSIGNOR TO STEPHEN SANFORD & SONS, OF AMSTERDAM, NEW YORK.

DESIGN FOR CARPET.

SPECIFICATION forming part of Design No. 29,352, dated September 13, 1898.

Application filed July 21, 1898. Serial No. 686,541. Term of patent 3½ years.

To all whom it may concern:

Be it known that I, GUSTAVE MARTIN FAUSER, a citizen of the United States, residing at New York city, in the county of New York and

5 State of New York, have invented and produced a new and original Design for Carpets; and I do hereby declare that the drawing accompanying this specification gives and conveys to any one skilled in the art of carpet-weaving a clear understanding of the same that is sufficient to enable such persons to use my invention.

10 My invention relates to a design to be worked into or upon carpeting or similar fabrics.

15 The said drawing is a face view of a carpet embodying my design.

The drawing illustrates a body and a border.

The body is in its aspect of ornamentation floral and scroll in the renaissance style. The 20 border is also in its aspect of ornamentation floral and scroll in the renaissance style.

What I claim, and desire to secure by Letters Patent, is—

1. In a design for carpeting, the body substantially as shown and described.
2. In a design for carpeting, the border substantially as shown and described.
3. The design for carpeting, consisting of the body and the border, substantially as 30 shown and described.

GUSTAVE MARTIN FAUSER.
